(57) **CLAIM**

The ornamental design for a football flagpole finial, as shown and described.

DESCRIPTION

FIG. 1 shows a perspective view of a first embodiment of a design for a football flagpole finial.

FIG. 2 shows a top view of the first embodiment.

FIG. 3 shows a bottom view of the first embodiment.

FIG. 4 shows a left side view of the first embodiment. A right side view of the first embodiment is the same as the left side view.

FIG. 5 shows a front view of the first embodiment. A back view of the first embodiment is the same as the front view.

FIG. 6 shows a view of the first embodiment of the football flagpole finial when placed on a flagpole.

FIG. 7 shows a perspective view of a second embodiment of a design for a football flagpole finial.

FIG. 8 shows a top view of the second embodiment.

FIG. 9 shows a front view of the second embodiment.

FIG. 10 shows a bottom view of the second embodiment.

FIG. 11 shows a left side view of the second embodiment. A right side view of the second embodiment is a mirror image of the left side view.

FIG. 12 shows a back view of the second embodiment; and, FIG. 13 shows a view of the second embodiment of the football flagpole finial when placed on a flagpole.

The broken-line features in the figures are for illustrative purposes only and form no part of the claimed design.
